C. BLAMFIELD

FIRE LIGHTER

Filed Sept. 16, 1925

Inventor,
Charles Blamfield;

By *A. B. Upshaw*,
attorney.

Patented Mar. 16, 1926.

UNITED STATES PATENT OFFICE.

CHARLES BLAMFIELD, OF BOSTON, MASSACHUSETTS.

FIRE LIGHTER.

Application filed September 16, 1925. Serial No. 56,631.

To all whom it may concern:

Be it known that I, CHARLES BLAMFIELD, a subject of the King of Great Britain, and a resident of the city of Boston, in the county 5 of Suffolk and Commonwealth of Massachusetts, have invented certain new and useful Improvements in Fire Lighters, of which the following is a full, clear, and exact specification.

10 The object of this invention is the construction of an improved means for igniting fires in stoves at a predetermined hour. In the construction of the same, I provide two relatively sliding members, one holding 15 the igniting element, as a match, and supported in close proximity to the combustible material to be ignited; and the other carrying a suitable friction surface designed to be drawn over the match by an elastic ele- 20 ment, but held from such action by a stop adapted to be very slowly weakened until it is forced to release the sliding member and to permit its friction surface to ignite the match and set fire to the combustible 25 material.

In the drawings forming part of this specification, Fig. 1 is a side view of a fire lighter embodying my invention. Fig. 2 is a side sectional view of the same showing 30 the parts set for its igniting operation. Fig. 3 is a top view of a portion of the stationary member. Fig. 4 is a cross section at 4—4 in Fig. 2.

35 The device as illustrated in the drawings is about full size and is mainly constructed of wood for the sake of economy. The stationary member 1 has its end designed to be nearest the fire sheathed with sheet metal 2, and provided with an anchoring device 40 3 consisting of a pin which can be stuck into any piece of wood at hand. Immediately back of this sheath 2 is a vertical hole 4 into which the match is to be placed, leaving only its head 5 exposed.

45 Slidable upon the member 1 is the member 6 which is retained thereon by means of an elastic band 7 having an anti-friction shoe 9 between it and the under surface of the stick 1. The fire-end of the member or stick 50 6 is cut away to leave an overhang 10 to which is cemented a friction surface consisting preferably of ground glass 11 having its ground surface beneath, and so inclined that its inner end is above the level of the 55 match-head 5 but its outer end is below, whereby when the member 6 is drawn to-

ward the left as viewed in the drawings, the friction surface will slidably engage and ignite the match. By having the band 7 elastic, the surface 11 will slide up and over 60 the match and as far to the left as its im- petus will carry it.

For thus moving the sliding member 6, I provide an elastic band 12 attached to the shoulder 13 of the same, and united at its 65 ends 14 in any suitable manner. The sliding member being held in the position shown in Fig. 2 and the elastic band 12 pulled and pressed into the slot 15, a sudden release of the member 6 will speed the surface 11 70 over the match and ignite it.

To provide a stop for the member 6 which will thus release it at any predetermined time, the member 1 is formed with a notch 16 into which is placed a slowly soluble or 75 softening tab 17; and at the rear of the mem- ber 6 is a small chamber 19 formed by cut- 80 ting away a portion of the stick 6 and fasten- ing a sheet metal pocket 20 about it, leav- ing a narrow slot 21 to receive the tab 17; 85 filling it with fibrous material or pieces of sponge 22, and covering it with a rubber flap 23 attached at 24 to the stick.

A liquid being introduced into the cup 85 or chamber 19 until the sponge or fibrous material therein is saturated, the moisture therefrom will very slowly creep down and be absorbed by the tab 17 until the latter has become soft enough to release the slid- 90 ing member 6.

When the match is ignited the movable member 6 has retreated toward the left en- 95 tirely away therefrom, so that the flame can rise from the match and set fire to the combustible material suspended from the kindlings above it.

When setting the lighter, the burned match is withdrawn and a fresh portion of one inserted in the hole 4; and the member is pulled slightly away from the member 1 to permit it to be passed over the match- 100 head; the elastic band 7 readily allows this. Then a fresh tab is inserted in the notch 16, and the rubber band 12 is stretched out into engagement with the slot 15.

These tabs may be composed of rosin and soda, or sugar; but I prefer fiber, either wood pulp or straw, impregnated with starch or gelatine, and treated with resin or the like.

110 A small transverse hole 25 is provided which cuts into the path of the hole 4 in

order, should an extra small match stem be used, another match or small stick can be inserted into the hole 25 to suitably contract the hole 4 and make the small match stay 5 in place.

The stick or board 26 to which the fire lighter is illustrated as attached by the pin 3, may carry a piece of fabric or wicking 27 saturated with paraffin wax, and thereby 10 supported so close to the match as to ensure its own ignition and also that of the combustible material above it.

The anchoring pin 3 is formed with a shank 30 loosely and removably engaging 15 the hook 31 fixed in the forward terminal portion of the stick 1, so that when the lighter is to be packed for transportation, the pin can be disconnected therefrom to permit of a narrow carton for containing 20 it.

What I claim as my invention is:

1. A fire lighter comprising two elongated members, and an elastic band confining them together, the band being attached 25 to one of the members and provided with an anti-friction plate between it and the opposite surface of the other member, one of the members being adapted to carry an igniting element, and the other a friction surface, an elastic means for relatively sliding said member and thereby igniting said element, one of said members having a transverse 30 notch, a stop adapted to enter said notch and thereby to hold the members in a set position, and means for causing said stop to discontinue its holding action after a predetermined lapse of time.

2. A fire lighter comprising two elongated members, means for loosely but slidably 40 uniting them, an igniting element adapted to be lighted by the sudden relative movement of the members, an elastic device adapted thus to actuate them, one of the members having a transverse notch, a tab 45 adapted to be introduced into said notch, a moisture carrying chamber adapted to be

put into contact with said tab when said members are in their set position, whereby said tab, being of softening material, will after a time be rendered incapable of longer 50 holding the members from action.

3. A fire lighter comprising two elongated members connected to be relatively slidable, an igniting element adapted to be lighted by the sudden movement of said members, an 55 elastic device adapted thus to actuate them, the stationary member having a transverse notch, the other having a chamber at its end opposite the igniting element for containing moisture-laden fibrous material, said chamber having a slot through its bottom, and a slowly softening tab adapted to be introduced into said notch and slot, whereby to hold said members in their set position until it has lost its power by the slow absorption 60 of the moisture.

4. A fire lighter comprising a stick, a metal shielding for one end thereof, the stick having a hole near the shield for receiving a match, a second stick slidable upon 70 the first one and having an overhung portion carrying a friction surface for igniting the match, the stationary stick having a slot in its end opposite to the shield, a rubber band attached to the slidable stick and 75 adapted to be anchored in said slot, the stationary stick having a transverse notch, the movable stick having a chamber provided with a rubber flap for a cover and a slot through its bottom and filled with 80 moisture carrying fibrous material, and a tab adapted to be introduced into said notch and last-named slot for holding the slidable stick in its set position against the urge of 85 said band, the tab being of a material adapted to be slowly softened by moisture and thereby release the slidable member.

In testimony that I claim the foregoing invention, I have hereunto set my hand September, 1925.

CHARLES BLAMFIELD
